UNITED STATES PATENT OFFICE.

WILLIAM S. HADAWAY, JR., OF NEW ROCHELLE, NEW YORK.

RANGE.

1,383,109.

Specification of Letters Patent. Patented June 28, 1921.

Application filed August 1, 1917. Serial No. 183,861.

To all whom it may concern:

Be it known that I, WILLIAM S. HADAWAY, Jr., a citizen of the United States of America, and a resident of New Rochelle, county of Westchester, and State of New York, have invented certain new and useful Improvements in Ranges, of which the following is a specification, reference being had to the accompanying drawings, forming a part 10 thereof.

My invention relates to heating and cooking apparatus, and has special reference to ranges which receive their heat in whole or in part, from a source of hot vapor such as 15 steam. It also pertains particularly to heaters of the aforesaid character in which electricity is utilized to supplement and control the vapor.

When steam or other vapor is utilized in 20 conjunction with electric energy for heating purposes, as for example, a cooking range, the most economical proportioning of the electrical energy used, relative to the heat energy supplied by the steam, is evidently 25 dependent in general, upon the cost of the fuel utilized in generating the steam and upon the cost of the electric energy available at the point of use.

In almost all cases where cooking ranges 30 are in demand the cost of heat supplied from a source of steam, is very much less than the cost of electrically generated heat and it has been my aim to provide a range suitable for use wherever electric energy is 35 available even though the cost of the electric energy may vary widely in different places.

One object of my invention is to provide 40 a simple and compact range structure that shall embody a sink unit in addition to steaming or boiling, roasting, frying and broiling compartments.

Another object is to provide a range of 45 the aforesaid character having a simple pipe connection and adapted to receive high temperature steam and utilize the same advantageously for low temperature as well as high temperature work.

In order that my invention may be thoroughly understood I will now proceed to 50 describe the same in the following specification and then point out the novel features thereof in appended claims.

Referring to the drawings:

Figure 1 is a partial sectional elevation 55 showing a range arranged and constructed in accordance with my invention and consti-

tuting an embodiment thereof, the source of steam and the connections being also illustrated.

Fig. 2 is a sectional elevation of the baking and warming ovens, together with the frying compartment, which are shown in the structure of Fig. 1 on the right-hand side of the range.

Fig. 3 is a sectional view showing a baking unit, adapted to be utilized within one of the ovens of Fig. 2, as hereinafter explained.

Fig. 4 is a corresponding view of a frying 70 pan.

Fig. 5 is a view corresponding to Fig. 2, of the steamer section of the range, together with the broiler which is mounted at the left in the range shown in Fig. 1.

In the drawings, 10 designates the range 75 structure which is shown mounted on legs 11 and comprises, in general, a high temperature oven 12, a low temperature oven 13, a steamer compartment 14, a broiler 15, a frying compartment 16, and a sink 17. The 80 whole range is preferably provided with a hood 18, which communicates with a flue 19.

20 designates the floor line and 21 may, for example, designate a basement floor on which is mounted a steam generator 22 hav- 85 ing a superheater 23.

24 designates a hot water tank having a heating coil 25 which is supplied with steam through a pipe 26, and is connected at its opposite end by a pipe 27 to the water sec- 90 tion of the generator.

28 designates a water main which is connected to the hot water tank by a pipe 29 and is connected to a cold water faucet 30 at the sink; a pipe 31 connects the hot water 95 tank to a hot water faucet 32.

The superheater 23 is connected at one end to the steam dome 33 of the generator by a pipe 34, and its outlet end is connected by a pipe 35 to a distributing pipe 36 at the 100 range, a temperature booster 37 being interposed if desired.

The distributing pipe 36 has a plurality of branches 38 to 43 inclusive, which are governed respectively by control valves 44 105 to 49.

The broiler 15 and the steamer 14 may be made in a single unit as shown in Fig. 5, having walls 50 of insulation, an insulating partition 51 which separates the broiler 110 from the steamer, and a sheet metal casing 52 which protects the insulation,

The interior of the steamer is preferably provided with a plurality of removable racks 53 and is lined to form a water tank 54 at the bottom and the steam-tight compartment above.

Disposed in the tank 54 is a superheater coil 55 which is connected to the branch 38 of the distributing pipe 36, from which it is supplied with high temperature steam.

10 As hereinafter explained, this high temperature steam is too hot to be used directly in a steamer for cooking vegetables and the like, and in the arrangement illustrated, the coil 55 constitutes a steam generator since it causes the water contained in the tank 54 to boil and fill the steamer with wet steam. As fast as the steam is condensed the water merely flows down the sides of the steamer and returns to the tank. The steam from 15 the coil 55 is allowed to discharge into the water but its temperature above the water is of course materially reduced before it reaches the discharge end of the coil.

20 The branch 39 is connected to coils 56 which are disposed in slabs 58 which form parts of the broiler and on which are supported radiant electric heaters 59.

25 The broiler forms no part of my present invention, and is preferably constructed as shown and described in my copending application Serial No. 82,071 filed March 4, 1916.

30 The branch 40 is connected to a steam outlet 60 which is disposed over the sink 17, and from which steam may be drawn for any desired purpose. The branch 41 is connected to the low temperature oven 13, the branch 42 to the frying compartment 16, and the branch 43 to the high temperature 35 oven 12.

40 The high temperature oven has a double insulating wall composed of an outer layer 61, an inner layer 62 and an interposed vapor passage 63 which is preferably filled 45 with sand or like particles to retard the flow of steam therethrough.

45 The high temperature oven is further provided with a lining 64 having relatively large heat capacity such as soapstone slabs 50 for example. The inner layer 62 of the insulation is preferably formed of a porous material having a small heat capacity such as silocel. The outer layer 61 may preferably be formed of slabs of magnesia or 55 some other suitable material for reducing the heat losses from the vapor passage or chamber 63.

60 Electric heaters 65 of any suitable structure are mounted on and may form a part of the inner wall of the oven.

65 As hereinafter explained, these electric heaters if used alone, would only maintain a relatively low temperature in the oven. In other words, they have a relatively small capacity and are inexpensive to operate.

The low temperature oven 13 is protected by the insulating wall 61 which is extended to inclose both ovens and to form a partition 66 between them. Within this insulation is a steam passage divided into two parts 67 and 68 within which is a relatively thick porous insulating lining 69 forming the inner walls of the oven.

70 The branch 41 is connected to the lower part 67 of the steam jacket and steam is adapted to flow from this jacket or space through the pores of the insulation 69 into the oven. It flows out through the porous insulation 69 on the opposite side and into the part 68 of the steam jacket. From this point it flows through outlet pipes 70 and is preferably discharged into the water tank of the steamer, although if desired, it may be discharged into the sink after it is 75 condensed.

80 The frying compartment 16 is disposed in a mass 72 of insulation having a steam space 73 which is shaped to conform to the contour of the opening in the receptacle produced by the metal lining 74 of the compartment. The space between the metal lining 74 and the steam jacket 73 is filled with porous insulation 75, a sheet metal partition 76 being preferably introduced as a baffle to cause the incoming steam which is admitted from the branch 42 to flow first through the space 73 and then from a point near the rim of the receptacle backwardly through the porous insulating mass 75, from which it escapes to the outlet pipes 77.

85 The outlet pipes 77 are joined to the pipe 70 so that the outgoing steam from the ovens 12 and 13 and from the frying compartment 16, is carried over and discharged to the steamer 14.

90 Within the ovens 12 and 13 are contact plugs 78 and 79 which are connected to short lengths of flexible cord designated 80, and are connected at their opposite ends to outlets 81.

95 In Fig. 3 is shown a baking dish or small oven designated 82 which comprises a receptacle section 83, a cover section 84, and electric heaters 85. The walls of the sections 83 and 84 are formed of insulating material having a considerable heat capacity and the electric heaters are connected to an outlet 86 which is adapted to coöperate with the connecting plug 79 in the oven.

100 Instead of having the flexible cord 80, a pair of spaced stationary contact members may be affixed at the back of the oven and guide rails provided to receive the baking dish in position to make contact with the stationary contacts within. The baking dish 115 as shown in Fig. 3, is intended as an illustration only, of one form which may be conveniently used within the oven, but it will of course be understood that dishes or receptacles of various shapes and sizes may be 120 125 130

used in either a high or low temperature oven, dependent upon the cooking operation to be accomplished.

The frying compartment 16 may be used directly as a heated cooking receptacle but I prefer to have an electrically heated frying pan or the like available for high temperature use. The frying pan may be made up in any suitable way and may for example, be composed of a pair of nesting sheet metal dishes or walls between which is disposed suitable electric heaters, the structure being completed by welding the side or edge walls together. A structure of this kind is shown in Fig. 4, 87 designating the electric heaters, 88 the sheet metal walls, and 89 the handle of the device.

The vapor supplied from the superheater 23 may be sufficiently hot so that no electrical booster is required for raising its temperature or its temperature may be raised by an electric booster as indicated at 37 in Fig. 1. The structure of the booster forms no part of my present invention and may be formed as shown and described in my co-pending application Serial No. 177,168 filed June 27, 1917.

In either case the temperature of the vapor in the distributor 36 may be assumed for convenience to be approximately 400° F. and therefore the soapstone slabs 58 of the broiler will be heated to this temperature. The electric heaters 59 will generate a relatively small quantity of heat at high temperature and their capacity is relatively small because of the fact that the slabs have a large heat capacity and are maintained at a fixed temperature only about 150° to 200° lower than the temperature required for broiling.

The hot vapor supplied to the steam generating coil 55 is obviously at a sufficiently high temperature to make the water in the tank boil rapidly and keep the entire space in the chamber of the steamer filled.

The steam admitted, as already explained, from branch 41 to the lower temperature walls, fixes the temperature of the walls and furthermore percolates through the porous inner walls 69 and fills the interior of the oven with an atmosphere of dry vapor at substantially the temperature of the incoming steam which is assumed to be about 400°.

If the baking dish is filled with material to be cooked and is placed in the oven 13, steam may then be turned on by operating the valve 48 and obviously the baking dish, including its walls 83 of suitable heat capacity, is heated to the temperature of the steam. Assuming that the electric connection was completed when the dish was introduced into the oven, electricity may be switched on to energize the heaters 85. The preliminary heating of the baking dish may

be accomplished when the dish is opened and the electric energy supplied to the heaters 85 after the dish is filled and closed. The size of the dish may be varied by introducing a hollow spacer 90 as shown in Fig. 3.

The walls of the dish constitute heated heat insulation and they act so as to necessitate only a rise in temperature of from about 400° to 550°, that is, about 150° rise instead of from room temperature of say 70° to 550°, that is, a rise of 480°.

It is therefore evident that the electric energy required is very small relative to that which would be necessary in case the baking dish were to be used in the atmosphere instead of in the oven.

The high temperature oven 12 may be compared to a low temperature oven with a dish of the character shown in Fig. 3 but of full size to fit the oven introduced.

As clearly shown in Fig. 2, the vapor holds the insulation of which the walls of the oven are composed, at a fixed temperature, say, about 400°, and the electric heater 65 raises the temperature to a desired working temperature within the oven with the expenditure of a small amount of energy. It is of course possible to utilize the baking dish 82 within the oven 12, and to either energize the heater 65 or not as desired.

I consider it preferable to utilize either the electric heaters 65 or the electric heaters 85 when the dish is used in the oven 12, but not to use both at the same time.

Attention is especially directed to the fact that the amount of electrical energy utilized in generating heat, may be easily governed so as to control the temperature existing irrespective of variations in the steam temperature.

The operation of the broiler is similar to that of the oven and baking dish. The steam heated frying compartment serves to maintain the heat of the frying pan at a fixed level, independent of the electrical heaters 87 which are called upon merely to supply sufficient heat to increase the temperature to the desired working level.

In the operation of the oven the vapor should thus first heat the heat insulation to its own temperature. The vapor is then depended upon to surround the heat insulation and prevent loss of heat therefrom and the electric heaters will raise the temperature only on the inside to the desired working level and will maintain and regulate the temperature required.

My invention may be embodied in structures of various kinds adapted for various uses, and I intend only such limitations as are indicated in the appended claims.

What I claim is:

1. A range comprising a high temperature steam distributer, a steamer having a water chamber, and a heating coil in the water

chamber connected to the high temperature steam distributer.

2. A cooking device comprising a chamber having walls of heated insulation, and 5 an electrically heated cooking appliance adapted to be disposed in the chamber.

3. A cooking device comprising a body of heat insulation, means for supplying heat thereto, a recess in the body, a metal lining 10 in the recess, and an electric heater in the form of a dish adapted to be fitted into the recess.

4. A cooking device comprising a body of heat insulation, means for supplying heat 15 thereto, a recess in the body, a metal lining in the recess, and an electric heater in the form of a dish removably mounted in the recess.

5. The combination with a heated chamber, of a baking dish adapted to be inserted 20 therein and having walls of heat insulating material of relatively large heat capacity, and electric heaters for heating the interior of the baking dish.

6. The combination with a heated chamber, of a baking dish adapted to be inserted 25 therein and having walls of heat insulating material of relatively large heat capacity, and means for generating heat within the baking dish.

7. The combination with a heated chamber and an electric circuit connector therein, of a baking dish having a connector to co-operate with the connector in the chamber 35 adapted to be inserted therein and having walls of heat insulating material of relatively large heat capacity, and electric heaters for heating the interior of the baking dish.

8. A range comprising a sink, a control 40 panel, a baking oven and a steamer at the respective ends of the sink.

9. A range comprising a sink, a control panel, a baking oven and a steamer at the 45 respective ends of the sink, and a hood overhanging the range.

10. A range comprising a sink, a control panel, a baking oven and a steamer at the 50 respective ends of the sink, and a frying compartment and a broiler beyond the oven

and steamer at the respective ends; and a hood overhanging the range.

11. An oven having an inner lining of heat insulation having large heat capacity, an intermediate covering of porous heat insulation having a relatively low heat capacity, and an outer wall of heat insulation spaced from the intermediate covering. 55

12. An oven having an inner lining of heat insulation having large heat capacity, 60 an intermediate covering of porous heat insulation having a relatively low heat capacity, an outer wall of heat insulation spaced from the intermediate covering to form a steam space, and means for supplying 65 hot vapor thereto.

13. An oven having an inner lining of heat insulation having large heat capacity, an intermediate covering of porous heat insulation having a relatively low heat capacity, 70 an outer wall of heat insulation spaced from the intermediate covering to form a steam space, grains or particles of heat insulating material in the steam space, and means for supplying hot vapor thereto. 75

14. A steamer comprising a steam space, a water tank communicating therewith, and a steam coil located in the tank arranged to discharge into the same and adapted to be supplied with superheated steam. 80

15. An oven comprising insulated walls, means for supplying heat to the walls, an electrical connector within the oven, and a closed receptacle having walls of large heat capacity, electric heaters within the receptacle, and means arranged to co-operate 85 with the connector in the oven.

16. A receptacle, an insulated mass surrounding the receptacle, means for heating the insulated mass, a frying pan adapted to 90 fit into the receptacle and having electric heaters for heating the same.

17. A range comprising a sink, a baking oven on one side, a steamer on the opposite side, a control panel over the sink, and a 95 hood overhanging the complete range.

In witness whereof, I have hereunto set my hand this 16 day of July, 1917.

WILLIAM S. HADAWAY, Jr.
